UNITED STATES PATENT OFFICE.

BERNARD TAUBER, OF NEW YORK, N. Y., ASSIGNOR TO INTERSTATE ELECTRIC NOVELTY CO., OF NEW YORK, N. Y., A CORPORATION OF NEW YORK.

ELECTRIC SWITCH FOR PORTABLE ELECTRIC LIGHTS.

1,187,565.

Specification of Letters Patent. Patented June 20, 1916.

Application filed November 13, 1913. Serial No. 800,706.

To all whom it may concern:

Be it known that I, BERNARD TAUBER, a citizen of the United States, and a resident of New York city, in the county of New York and State of New York, have invented certain new and useful Improvements in Electric Switches for Portable Electric Lights, of which the following is a specification.

10 The invention pertains more particularly to improvements in the class of electric lamps designed to be held in the hand and sometimes used as flash lights and at other times for affording a permanent light for a short period, and the object of the invention is to provide a novel and efficient circuit closer for a lamp of the class referred to.

The circuit closer of my invention comprises an exterior casing to be secured to the shell of the lamp, a contact spring concealed within the chamber of said casing, and a slide mounted on the casing and guided thereby and having within the casing a projection to engage the closing spring and flexing said spring to close the circuit when the slide is moved for that purpose. When the slide is moved to force the circuit closing spring into operative position, said slide may be released from the pressure of the hand since it has no tendency to automatically return to its inoperative position. The slide is adapted to be readily moved along the top of the casing by the pressure of the thumb of a person holding the lamp, and hence said slide may be moved to complete the circuit or to break the circuit as quickly as may be desired, and likewise the slide, when moved to a position to complete the circuit, may be left there so as to hold the circuit closed for any desired period.

40 The invention will be fully understood from the detailed description hereinafter presented, reference being had to the accompanying drawings, in which:

45 Figure 1 is a side elevation of a portable electric light embodying my invention; Fig. 2 is a vertical section through the same on the dotted line 2—2 of Fig. 1; Fig. 3 is a detached view of the inner side of the casing for the spring contact and slide, said spring being shown in position within said casing; Fig. 4 is a corresponding view of the same, with the contact spring omitted from the casing; Fig. 5 is a horizontal section through the flash light on the dotted line 5—5 of Fig.

2; Fig. 6 is a horizontal section on an enlarged scale through a portion of the flash light taken on the dotted line 6—6 of Fig. 2; Fig. 7 is a vertical section through a portion of the flash light, corresponding with the section of Fig. 2 but illustrating a modified form of contact spring within the casing; Fig. 8 is a like view showing a further modified form of contact spring within the casing; Fig. 9 is a detached perspective view of the contact spring illustrated in Fig. 7; Fig. 10 is a detached perspective view of the contact spring shown in Fig. 8, and Fig. 11 is a sectional view corresponding with Figs. 7 and 8 and showing a still further modification in respect to the contact spring.

In the drawings, 15 designates the usual paper or fiber casing for the flash light, 16 the battery therein, 17 the lens, 18 the electric lamp bulb, 19 the reflector, 20 the electric connection of the battery with the lamp and 21 the usual electrical conductor connection between the metallic cap 22 and the lower terminal of the battery 16. Within the casing 15 are two customary conductors 23 or strips of metal 23, 24, the lower end of the conductor 24 being in electrical connection with the metal cap 22, as usual, and which cap is ordinarily screwed upon a metal sleeve 25 fastened around the lower end of the casing 15. The upper end of the conductor 23 is in electrical connection with the reflector 19 and said reflector and lens 17 are, as is customary, held in position by means of a threaded metal sleeve 26 screwed upon a metal sleeve 27 fastened around the upper end of the casing 15. The parts hereinbefore identified by reference numerals are of customary known character and construction, and my invention has to do with the means I have provided for closing the circuit between the conductors 23, 24.

Upon the outer side of the casing 15 I secure by rivets 28, 29 or otherwise a sheet metal casing or escutcheon 30 which has a raised central longitudinal box portion 31 forming therein a chamber 32 within which is confined my circuit closing spring 33, said spring in width being about the width of the chamber 32 and in length about the length of said chamber and generally conforming to the outline of said chamber, as may be understood by reference to Fig. 3. The rivet 29 places the casing or escutcheon 30 in electrical connection with the conductor 24, said

rivet passing through said casing and conductor at the upper end of the latter. The lower end of the conductor 23 terminates in the plane of the upper end of the spring 33, 5 whereat a rivet 34 extending through the casing 15 secures the lower end of said conductor 23 and affords a projecting head within the chamber of the casing 30 to make electrical connection with the upper end of the 10 spring 33, as shown in Fig. 2, when said spring is depressed inwardly against said rivet. In the position of the parts shown in Fig. 2, the upper end of the closing spring 33 is free of the head of the rivet 34, and hence 15 the circuit is not complete and the lamp under such condition will remain dark.

Upon the outer face of the box-portion 31 of the casing 30 is mounted a slide 35 to be moved by the pressure of the thumb 20 or finger toward and from the upper end of said box-portion 31, according to whether it is desired that the spring 33 shall complete or close the circuit or move to a position breaking the circuit through the lamp. 25 The slide 35 has near its upper end lugs 36 which project through slots 37 in the top of the box-portion 31, and during the movement of the slide 35 said lugs coöperating with the edges of said slots serve to aid in 30 guiding the slide. The lugs 36 are, however, intended more particularly to coöperate with the closing spring 33 in the manner hereinafter described. The slide 35 has near its lower end lips 38 which, after being 35 projected through the lower ends of the slots 37, in the box-portion 31 of the casing 30, are bent laterally toward each other and upon edges of the washer plate 39 which is cut out at its side edges to receive 40 said lips and which extends laterally beyond the slots 37 and serves, in connection with the lips 38, to bind the slide 35 in position and prevent said slide, when operated, from having undue looseness of movement 45 or from tilting outwardly from the surface of the box-portion 31 of the casing 30. The lips 38 and washer plate 39 serve as securing and guiding means for the slide 35.

The circuit closing spring 33 may be of 50 varied formation within the scope of my invention, and in Figs. 2 and 3 I illustrate the preferred construction and arrangement of said spring. The spring 33 is a plain strip of metal set loosely within the chamber 32 of the casing 30, and said spring has a bend or pocket 40 formed in it in the plane of the lugs 36 on the slide 35 when said slide is in its initial or inoperated position, as shown in Fig. 2. Above the bend or 60 pocket 40 the upper end of the spring 33 stands outwardly close to and may touch, without detriment, the upper inner longitudinal wall of the box-like portion 31 of the casing 30, and below the pocket or bend 65 40 the spring is bent toward and lies against

the exterior surface of the casing 15, as at 41, and below this portion 41 of the spring which is a bearing portion engaging the casing 15, the spring is bent or deflected outwardly to the lower outer corner of the chamber 32, said lower end, which I number 42, of the spring serving as means for keeping the bearing portion 41 against the casing 15. When it is desired to complete the circuit 70 through the lamp, the slide 35 will be moved outwardly in a direction toward the lens end of the flash-light, and during its movement the lugs 36 carried thereby and initially in the pocket 40 of the spring 33, will ride upwardly on the upper portion of the spring 80 and outwardly from the pocket 40, and thereby operate as wedges to force the upper end of the spring against the adjacent head of the rivet 34 and thereby complete or close the circuit through the lamp. The 85 slide 35 may be left in its operative position so long as it may be desired that the lamp shall be lighted, and thereafter the user of the flash-light will move the slide 35 back to its initial position shown in Fig. 2 and 90 thereby carry the lugs 36 in the plane of the pocket 40 and permit the spring 33 of its own resiliency to move outwardly at its upper end from electrical connection with the rivet 34, the circuit being thereby broken. 95 When the slide 35 is moved to its operative position and the lugs 36 thereon bend the upper end of the spring 33 to engage the rivet 34, said spring has two bearing points, one being at 41 against the outer wall of the 100 casing 15, and the other being at the extremity of the lower end 42 of the spring, said extremity being confined by the outer interior wall of the box 31. It will be noticed that the spring 33 is simply a plain strip of 105 metal suitably bent to form the pocket and bearing points and not requiring to be riveted or otherwise fastened to the box 31 or slide 35. I form a slight depression 43 at the upper end of the spring 33 as a means 110 of assuring a ready contact of the upper end of the spring with the head of the rivet 34. It is to be noticed also that while the slide 35 has movement imparted to it the spring 33 remains substantially stationary 115 except for the flexing it receives from the lugs 36 and for the resiliency it exerts in returning to its normal position when said lugs are moved back to the plane of the pocket 40, said pocket being merely a curvature formed in a strip of metal constituting 120 the spring 33.

It is my desire that this application be not limited to the special formation of the spring 33 shown in Figs. 2 and 3, and therefore I illustrate in Figs. 9, 10 and 11 some modified forms of springs which can readily be used with the other features of my invention.

In Fig. 9 the spring is formed with two 125

depressions or pockets 44 to receive the lugs 36, and instead of having the long bearing 41 shown in Fig. 2, is formed with two bearing points 45, 46, these two bearing points 5 being merely a subdivision of the one elongated bearing 41 shown in Fig. 2. The depressions 44 take the place of the transversely elongated pocket 40 of the spring 33 shown in Figs. 2 and 3. I illustrate in 10 Fig. 7 the spring shown in Fig. 9, and which for convenience I will number 47, in position in the box 31, there being no change in the box whether the spring 33 or the spring 47 is used therein.

15 In Fig. 10 I illustrate a further modified form of spring in that the spring, which for convenience I number 48, is formed below the pocket 49 for the lugs 36 with a spring tongue 50 cut therein and bent inwardly to engage the outer wall of the casing 15 as I illustrate in Fig. 8. The presence of the spring-tongue 50 adds flexibility to the closing spring.

20 In Fig. 11 I illustrate a further form of spring 51 in the box 31, this spring having a pocket for the lugs 36 and a turned over upper end for engagement with the rivet 34, and the lower end of this spring being attached to the casing 30 by a lump of solder 30 52. I prefer the constructions of closing spring which do not require any additional means for securing them in place and not requiring any means for permanently attaching them to the casing 30.

35 In all of the forms of the invention illustrated the spring remains substantially stationary, except for its flexing during the movements of the slide 35, and the lugs 36

on said slide operate in all the forms of the invention illustrated as wedges to force one 40 end of the closing spring 33 into circuit closing position.

What I claim as my invention and desire to secure by Letters Patent, is:

For an electric flash light of the class described having a main shell and circuit terminals, circuit closing mechanism comprising an exterior chambered casing secured on said shell and in permanent electrical connection with one of said terminals, 50 a leaf-spring confined within and extending lengthwise of the chamber of said casing and having one end over and normally spaced from an end of the other of said terminals which extends into said chamber, 55 and a manually operative slide mounted on said casing having a lug extending into the chamber thereof for engaging and flexing said spring against said end of said other terminal when the slide is moved to operative position, said spring being a leaf spring bent outwardly at its contact end to normally clear said end of said other terminal and having back from said end a depression to receive the inner end of said 60 lug when the slide is in its inoperated position, and said spring being in electrical engagement with said casing and substantially fitting the chamber thereof.

Signed at New York city, in the county 70 of New York and State of New York, this 11th day of November, A. D. 1913.

BERNARD TAUBER.
